GILL DRAWING FRAME

Willie Holdsworth, Providence, R. I.

Application October 22, 1931. Serial No. 570,281

7 Claims. (Cl. 19—129)

This invention relates to faller-bars for gill-drawing frames and particularly to improvements in the construction and method of operation of the same.

5 A principal object of the invention is to provide an improved faller-bar which will operate with greater efficiency to straighten and disentangle the fibers in the gill-box or drawing frame whereby a more completely and uniformly combed product is produced.

The present improved faller-bar is intended for use in gill-boxes or drawing frames of the so-called "French" or "Swiss" type, wherein two opposed sets of bars are arranged with their teeth or pins extending into the fibers from opposite directions and intersecting, and the invention has for its object to so construct the bar that the teeth on both sets of bars will project completely through the mat of fibers being treated.

20 Another object of the invention is to provide a faller-bar of the type specified so constructed at its pin-holding edge as to provide a clearance for the points of the pins or teeth of an opposed bar whereby to permit both sets of teeth to project clear through the fibers being combed.

25 Another object of the invention is to provide an improved faller-bar of the type specified which is of strong and sturdy construction and durable in use over long periods of time.

30 Further objects of the improvements are set forth in the following specification which describes several preferred embodiments of the invention, by way of example, as illustrated by the accompanying drawings. In the drawings:

35 Fig. 1 is a longitudinal elevation of the faller-traversing mechanism at one side of a gill-drawing frame and illustrating the present improved faller-bar as applied to use therewith;

40 Fig. 2 is a cross-sectional view taken on line 2—2 of Fig. 1 and showing two opposed faller-bars in operative engagement with the traversing-screws at both sides of the machine;

45 Fig. 3 is an enlarged cross-sectional view taken through a series of the upper and lower faller-bars and illustrating the intersecting relation of their teeth or pins;

Fig. 4 is a similar cross-sectional view showing a modified form of the faller-bar;

50 Fig. 5 is a similar cross-sectional view showing a further modified form of construction of the faller-bar; and

Fig. 6 is a similar view illustrating a still further modification in the construction of the faller-bar.

55 In gill-drawing frames of the so-called

"French" or "Swiss" type two sets of opposed faller-bars are employed for combing the fibrous material fed through the machine. The upper and lower sets of bars are arranged in staggered relationship with their teeth or needles penetrating 60 into the material from opposite directions to form a double comb passing through the fibers to straighten and lay them in parallelism. The faller-bars rest on horizontal saddles and are slid longitudinally therealong by means of traverse-screws 65 which engage their end-portions.

Heretofore, in the construction of faller-bars for machines of the type specified, the length of the intersecting teeth or pins on the opposed bars is governed by the distance between the bottom 70 edge of the upper bar and the top edge of the lower bar. That is to say, it has always been considered necessary to make the pins of a length slightly less than the distance between the opposed bars in order to provide clearance so that 75 the points of the pins will not strike against the edges of the bars.

With this previously used construction and arrangement of the bars the teeth will not penetrate clear through the mass of fibers, the path of 80 which is confined to the space between the edge of the bottom bar and that of the upper bar, so that all of the fibers do not receive a maximum combing action. Stated briefly, the central portion of the mass may be thoroughly combed while 85 its upper and lower portions are but partially treated. For example, where the teeth of the two oppositely positioned sets of bars fall short of the space between the bars the centrally disposed portion of the mass receives a complete combing action by all of the teeth on both sets of bars, but 90 the fibers at the extreme top and bottom portions of the mass are but partially combed by contact with the teeth of one set of bars, that is the bottom or top bars respectively.

95 It is a particular object of the present invention to overcome this deficiency of gill-drawing frames heretofore used by providing means whereby the teeth of both sets of opposed faller-bars will extend clear through the fibrous mass 100 being combed. To accomplish this result I construct the faller-bar to provide a clearance for the points of the teeth on the opposite bar whereby the teeth may overlap the edges of the bars. One form of construction for this purpose provides each bar with a longitudinally extending groove into which the points of the teeth of an opposite bar may enter. Through this construction and arrangement a maximum combing action is effected by all of the teeth on both sets 110

of bars which project clear through the mass of material to thoroughly and uniformly comb the fibers.

Fig. 1 of the drawings illustrates the arrangement of the traversing-mechanism of a French or Swiss type of gill-drawing frame such as disclosed in my co-pending application for United States Letters Patent, Serial No. 457,062, filed May 29, 1930. As the present invention relates more particularly to the improved faller-bar for use in such a form of machine, the traversing-mechanism is herein described only in brief as related thereto. It will be understood, however, that the traversing means shown in Fig. 1 has its duplicate at the opposite side of the machine as indicated in Fig. 2 of the drawings.

In the present type of gill-drawing frame the two opposed sets of faller-bars 9 and 10 are arranged with their pins intersecting to be traversed in the same direction during their working stroke and then carried back in the opposite direction at a different level to be once more traversed in the first direction. The traversing motion of the bars is accomplished by two pairs of traverse-screws at each side of the machine, the threads of which engage the ends of the bars to slide them on their horizontal saddles or rests 30, 31, 32 and 33 to be later described. Fig. 1 illustrates the traverse-screws at one side of the machine, the two intermediate screws being employed for traversing the opposite sets of bars 9 and 10 during their working stroke, after which the bars are transferred to the lower and upper screws, respectively, to be traversed in the opposite direction and transferred back to the first-mentioned screws. The four screws at either side of the machine are herein referred to as grouped in pairs for convenience of description. The lower pair of screws 2 and 3 operate on one set of bars 9 and the upper pair 4 and 5 on the bars 10 of the other set. The intermediate screws 2 and 4 have threads of relatively fine pitch to traverse the bars with a slow movement during their operative stroke, while the bottom screw 3 of the lower pair and the top screw 5 of the upper pair have coarser threads of longer lead to traverse the bars at a faster rate in their return stroke.

The several screws 2, 3, 4 and 5 are journaled in a bearing block 6 formed as a part of, or attached to, the side frame of the machine and the bottom screw 3 of the lower pair is usually constituted as a driving element for the other screws. As herein illustrated the bottom screw 3 is constructed integral with a shaft or spindle 7 which, besides being journaled in the block 6, has a separate journal in a bearing 8 bolted to the machine frame. At this end of the shaft 7 is a bevel-gear 18 arranged to mesh with a similar gear, not shown, on the main drive-shaft of the machine. The screw 3 carries a spur gear 19 meshing with a similar gear 20 on its companion screw 2 and the gear 20, in turn, meshes with a similar gear 21 on the next upper screw 4, while the gear 21 meshes with a gear 22 on the uppermost screw 5. In this manner the four screws 2, 3, 4 and 5 are connected to be driven together in unison. It will be seen that the intermediate screws 2 and 4 turn in opposite directions and their threads are of opposite hand in order to provide for the traverse of the two sets of faller-bars 9 and 10 in the same direction, or to the right as viewed in Fig. 1. The bottom screw 3 of the lower pair and the top screw 5 of the upper pair turn in a direction

opposite to that of their associated screws 2 and 4 and therefore have threads of the same hand, respectively, in order to traverse the bars through their return movement.

The faller-bars 9 and 10 slide on their fixed saddles 30, 31, 32 and 33 during their traverse in opposite directions and cams are provided at the ends of the screws for transferring the bars from one screw to another. As illustrated and described more in detail in my copending application for patent hereinbefore referred to, the screw 2 has cams 35 at its right-hand end for successively shifting the faller-bars 9 down across the end of the saddle 31 at the completion of their traverse to the right, whereby to engage them with the threads of the bottom screw 3 which traverses them back in the opposite direction for reengagement with the threads of the screw 2 once more. At the left-hand end of the bottom screw 3 are cams 36 which act on the bars 9 to lift them off from the saddle 30 and transfer them back into engagement with the threads of the screw 2. The screws 4 and 5 have cams 37 at the right-hand end of the screw 4 acting to raise the faller-bars 10 upwardly across the end of the saddle 33 to engage them with the threads of the screw 5; and the cams 38 on the left-hand end of the screw 5 operating to carry the faller-bars 10 down into the leading end of the threads of the screw 4 after the bars have been returned from the end of their operative stroke.

The several traverse-screws rotate in unison at the same rate of speed and the two intermediate screws 2 and 4 which traverse the bars 9 and 10 during their operative stroke are so timed with respect to their thread-grooves that the opposite sets of bars 9 and 10 have a staggered relationship during their traverse. That is to say, the opposed bars of the upper and lower sets instead of being arranged in line with each other are set in staggered relationship or one slightly in advance of another. It will also be noted by reference to Fig. 2 of the drawings that the teeth 11 on the opposed bars 9 and 10 are arranged in staggered or offset relationship longitudinally of the bars. Due to this arrangement the teeth on the opposed bars intersect to adapt them to be drawn through the fibers to provide a double combing action.

It has been stated that with the present improved form of faller-bar the opposite teeth are arranged to extend completely across the space between the upper and lower bars with their points overlapping the edges of the latter. To secure this arrangement I may employ any suitable form of construction of the bar as illustrated in the enlarged sectional views, Figs. 3, 4, 5 and 6. The bars 9 and 10 are of conventional type in general, having a relatively narrow central bridge-portion 12 with enlarged ends 13, the extremities of which are formed at the proper inclination to adapt them to engage freely in the helical grooves of the traverse-screws. The pins or teeth 11 are spaced along the longitudinal edge of the portion 12 of each bar and may be mounted in any suitable manner, for example, by soldering them in drilled holes in the bar.

In order to provide a clearance for the points of the pins or teeth 11 on the opposite bars I may form the main or bridge-portion 12 of each bar 9 and 10 with a groove or recess 14 extending longitudinally of its upper or lower edge as the case may be. That is to say, the lower bar 9 has a groove 14 extending along one side of its up-

per edge with the pins or teeth 11 held in holes at one side of the groove, while each upper bar 10 is formed with a recess extending along its lower edge as illustrated in Fig. 3. When the 5 bars are assembled in the machine with their ends in engagement with the threads of the screws 2 and 4, as illustrated in Fig. 1, the pointed ends of the pins or teeth 11 project into the recesses 14 whereby they may overlap the sides 10 of the bars to adapt them to penetrate clear through the mass of material represented at F in Fig. 3. It will be observed by reference to this view that the bat or mass of fibers is fed through the machine in a path confined between the upper 15 edges of the lower bars 9 and the bottom edges of the upper bars 10 so that fibers are never outside the range of action of the teeth 11 on the opposite bars 9 and 10.

Fig. 4 illustrates a slightly different form of construction of the faller-bars 9 and 10 wherein both sides of the bars are grooved or recessed along their edges adjacent the rows of pins or teeth 11. In this case the two opposite grooves or recesses 15 on the edges of adjacent bars provide the clearance for the pointed ends of the teeth 11, whereby the latter are adapted to project clear through the mass of material confined to the space between the upper and lower bars.

Fig. 5 illustrates a still further modified form of construction of the bars, the upper edges of the lower bars 9 and the bottom edges of the upper bars 10 being chamfered off on the side at 16 to provide the clearance for the points of the 35 pins or teeth 11.

Fig. 6 shows a construction of the bars similar to that illustrated in Fig. 5 except that the edges of the bars are chamfered on both sides at 17 to provide V-shaped clearance spaces for 40 the points of the teeth.

The present improved faller-bar may be constructed in accordance with any of the forms illustrated in Figs. 3, 4, 5 and 6 whereby to provide a clearance for the points of the intersecting 45 teeth or pins which may thus have their ends overlapping the sides of the bars to insure a complete penetration of the teeth through the fibrous material. The present forms of construction are illustrated only by way of example, however, 50 since other variations may be made in the shape or form of the pin-holding portion of the faller-bar to provide the clearance for the points of the teeth. When employed in the gill-box or drawing frame the present improved faller-bar operates in the manner as next explained.

The fibrous material, indicated at F in Fig. 3, is fed through the drawing frame by means of drawing-rolls not herein illustrated as they may be of any usual type as well known to those 60 versed in the art. As the mat or bat of fibers F feeds between the two sets of faller-bars 9 and 10 the latter are traversed longitudinally of the material in a direction opposite to the feed thereof. The bars 9 and 10 of the two opposite sets 65 are carried into position by the cams on the traverse-screws to impale their teeth or pins 11 through the mass of fibers and the bars then travel along the saddles 31 and 32 with their pins intersecting in staggered relationship as illustrated in Figs. 1 and 2. It will be observed by 70 reference to these views that due to the peculiar and novel form of construction of the present improved faller-bar all the pins or teeth on both sets of bars are caused to project clear through 75 the mass of material passing between the bars

so that no portion of the fibers may escape a complete combing action.

The operative stroke of the faller-bars is continuous during the rotation of the traverse-screws 2 and 4 and as each pair of opposed bars 9 and 10 reach the end of their traverse along the saddles 31 and 32 they are replaced at the opposite end by other bars returned to position by the screws 3 and 5 and transferred into the threads of the screws 2 and 4 by the cams 36 and 38, previously referred to. In this manner the fibrous material passing through the gill-box or drawing frame is given a complete and thorough combing to straighten the fibers and lay them in parallelism to prepare them for future processes by which they are converted into thread or yarn.

With the present improvement all portions of the fibrous mass are combed or gilled uniformly and thoroughly, due to the complete penetration 95 of the teeth on the faller-bars through the mass, and none of the fibers may escape thorough combing action and thus cause defects in the finished product.

The present invention thus provides for a more 100 efficient combing action of the faller-bars in the gill-box or drawing frame, resulting in a uniformly combed and improved product. That is to say, by the ingenious and novel form of construction as herein illustrated and described the 105 improved faller-bar is rendered much more efficient for the purpose intended whereby to enhance the value of the process to which it is applied by greatly improving the product.

While I have herein shown several preferred 110 forms of construction of the invention, by way of example, it is to be understood that further modifications may be made in the shape of the faller-bars and the disposition of their teeth, whereby to provide the improved result specified, 115 without departing from the spirit or scope of the invention. Therefore, without limiting myself in this respect, I claim:

1. In a gill-drawing frame, the combination of 120 opposite traverse-screws, and two sets of gill-bars extending between the opposite screws with their ends in engagement with the threads thereof, said bars having teeth projecting from their opposed edges in intersecting relationship and recesses between the sides of the bars for receiving 125 the points of the opposite teeth to provide for their penetration completely through the mass of material fed between the bars.

2. In a gill-drawing frame, the combination of upper and lower pairs of traverse-screws at 130 the opposite sides of the machine, and two sets of faller-bars extending between the opposite screws with their ends in engagement with the threads thereof, said bars being provided with projecting teeth spaced along their edges with the 135 teeth of one set intersecting those of the opposed set and said bars constructed to provide a clearance for the pointed ends of the teeth whereby they are caused to overlap the sides of the bars.

3. In a gill-drawing frame, the combination 140 of traversing means, and two sets of faller-bars traversed by said means in opposite parallel paths, said bars having spaced teeth projecting in opposite directions across the space between the bars and said bars being provided with openings along their sides for receiving the points of the teeth.

4. In a gill-drawing frame, the combination of 145 two sets of gill-bars arranged to be traversed in opposite parallel paths and provided with teeth 150

projecting from their edges across the space between the bars, said bars having clearance spaces between the pin-holding portions of adjacent bars for receiving the points of the pins on the opposite set of bars.

5. In combination, opposite sets of faller-bars adapted to be traversed in parallel relationship, said bars being provided with projecting teeth spaced along their edges, and each bar of a set 10 having its longitudinal edge portion cut away on the side to form a section of less thickness than the main section of the bar whereby the points of the teeth on one bar may project into the space at the side of the narrowed section of 15 an opposite bar.

6. In combination, opposite sets of faller-bars adapted to be traversed in parallel courses, said bars carrying projecting teeth spaced therealong,

and each bar of a set having its longitudinal portion chamfered on its lateral edge adjacent the row of teeth to provide that when the bars of the opposite sets are traversed with their teeth in parallel relationship the points of the teeth on 80 one bar may project into the space formed by the chamfered side of an opposite bar.

7. In combination, opposite sets of faller-bars adapted to be traversed in parallel courses, said bars having spaced teeth projecting therefrom, 85 and each bar of a set having a recess extending along one edge at the side of the teeth to provide that when the bars are traversed in opposed relationship the points of the teeth on one bar may project into the recess at the side of an 90 opposite bar.

WILLIE HOLDSWORTH.
